UNITED STATES PATENT OFFICE.

ARTHUR H. LOHSE, OF NEW YORK, N. Y.

FASTENER FOR BUTTONS.

SPECIFICATION forming part of Letters Patent No. 633,868, dated September 26, 1899.

Application filed March 20, 1899. Serial No. 709,796. (No model.)

To all whom it may concern:

Be it known that I, ARTHUR H. LOHSE, of the city of New York, borough of Manhattan, in the county and State of New York, have 5 invented new and useful Improvements in Fasteners for Buttons, Hooks, and Eyes, of which the following is a full, clear, and exact description.

This invention relates to improvements in 10 devices for fastening buttons, hooks, and eyes to garments or fabrics; and the object is to provide a simple device by means of which a button, hook, and eye may be quickly secured in place without the use of thread, as is the 15 usual method.

I will describe a fastener for buttons, hooks, and eyes embodying my invention and then point out the novel features in the appended 20 claim.

Reference is to be had to the accompanying drawings, forming a part of this specification, in which similar characters of reference indicate corresponding parts in all the figures.

Figure 1 is a perspective view showing a 25 button and the several parts of the fastener dismembered. Fig. 2 is a bottom view of a button with the fastener thereon. Fig. 3 is a sectional view indicating the position of parts before attaching the button to a garment, and Fig. 4 shows the button as attached.

Referring to the drawings, 1 designates a button of any suitable material and provided with perforations or eyes. To the under side of the button a metal plate 2 is secured. I 30 have here shown the plate as secured to the button by means of a rivet 3, passing through

an eye of the button and through the plate. At the end of the plate adjacent to the rivet 3 is a tongue 4, and passing through an eye of the button directly opposite to that receiving the rivet and also through the plate 2 is a fastening-pin 5, which is inclined toward the tongue 4, as plainly shown in Figs. 1 and 3.

In fastening a button the pin 5 is to be forced through the cloth α . Then the pin-point is to 45 be pressed outward through the cloth and the tongue turned down upon the end of the pin. Obviously a button fastened in this manner cannot become loose or torn off, and, further, by the use of my fastener a considerable 50 amount of time is saved in attaching buttons to a garment.

While I have shown and described my fastener in connection with a button, it is to be understood that it may be used for securing 55 hooks and eyes.

Having thus described my invention, I claim as new and desire to secure by Letters Patent—

The combination with a button having eyes 60 through it, of a plate, a rivet passing through an eye of the button and through the plate, a pin extending through another eye of the button and through the plate, the said pin and rivet serving to hold the button and plate together, and a tongue on the plate adapted to be turned against the pin, substantially as 65 specified.

ARTHUR H. LOHSE.
